UNITED STATES PATENT OFFICE.

JOSEPH J. KOVAR, OF OWATONNA, MINNESOTA.

CULTIVATOR.

1,418,807.

Specification of Letters Patent. Patented June 6, 1922.

Application filed October 31, 1919. Serial No. 334,680.

To all whom it may concern:

Be it known that I, JOSEPH J. KOVAR, a citizen of the United States, residing at Owatonna, in the county of Steele and State 5 of Minnesota, have invented certain new and useful Improvements in Cultivators; and I do hereby declare the following to be a full, clear, and exact description of the invention, such as will enable others skilled in the art 10 to which it appertains to make and use the same.

My invention has for its object to provide a highly efficient cultivating machine especially adapted for use in cultivating corn 15 and the like. To this end, it consists of the novel devices and combinations of devices hereinafter described and defined in the claims.

In the accompanying drawings, which 20 illustrate the invention, like characters indicate like parts throughout the several views.

Referring to the drawings:—

Fig. 1 is a plan view of the improved 25 cultivator, with some parts broken away;

Fig. 2 is a side elevation of the same;

Fig. 3 is a view partly in rear elevation and partly in transverse vertical section taken on the line 3—3 of Fig. 2;

Fig. 4 is a detail view principally in trans- 30 verse vertical section taken on the line 4—4 of Fig. 2, on an enlarged scale;

Fig. 5 is an outside elevation of the parts shown in Fig. 4;

Fig. 6 is a detail view principally in section 35 taken on the irregular line 6—6 of Fig. 3, on an enlarged scale;

Fig. 7 is a fragmentary detail view in side elevation with some parts sectioned on the line 7—7 of Fig. 3;

Fig. 8 is a fragmentary perspective view 40 of the connection between one of the ground-working tools and the respective supplemental frame; and

Fig. 9 is a plan view of the pointed end 45 of one of the ground-working tools.

The numeral 10 indicates a draft pole, to the rear end of which is rigidly secured a main frame 11. A draft equalizer 12 is pivoted to the pole 10, and a seat 13 of an operator is secured to the main frame 11. The main frame 11 is supported on the intermediate tubular member 14 of a three-part yoke-like axle and pivotally secured thereto by clip-like bearings 15. The end 50 members 16 of the axle are L-shaped and the horizontal arms thereof are telescoped

into the ends of the axle member 14 and adjustably secured thereto by longitudinally splitting the ends of said member 14 and placing therearound clamping collars 17. 60 These clamping collars 17 are preferably mounted in annular grooves formed in the axle member 14 to hold the same against axial movement thereon.

The vertical or down-turned arms on the 65 axle members 16 are pivoted in upright tubular bearing sleeves 18 having on their lower ends co-operating half-bearings 19 connected by draw-bolts 20. The inner ends of a pair of axially aligned trunnions 21 are 70 clamped between the half-bearings 19 and held against axial movement therein by forming thereon annular collars 22 which are mounted in correspondingly formed grooves 23 in said half-bearings. A pair 75 of large main wheels 24 is journaled on the trunnions 21 and held against removal therefrom by nuts 25 which have screw-threaded engagement with the outer ends of the trunnions 21.

The main wheels 24 are connected for 80 simultaneous steering movement by securing to the upper ends of the bearing sleeves 18 forwardly projecting arms 26, the free ends of which are connected by a transverse tie-bar 27 having an intermediate yoke 28. To impart steering movement to the main wheels 24, and also hold the same against pivotal movement on the axle members 16, there is secured to the upper ends of the 85 bearing sleeves 18 a pair of inwardly projecting foot levers 29 arranged to be controlled by an operator seated in the seat 13 and with his feet resting on said levers. These foot levers 29 also act as foot rests 90 for the operator.

Underlying the main frame 11 is a pair 95 of supplemental frames 30 that are laterally spaced and each thereof is connected to the draft pole 10 by an upwardly and forwardly inclined drag bar 31, the forward end of which is curved inward and pivoted at 32 to said pole to permit horizontal transverse swinging movement of the respective supplemental frames 30. The rear ends of the 100 drag bars 31 are connected to the supplemental frames 30 by pairs of nut-equipped bolts 33, the rearmost of which in each pair are extended through upright slots 34 in the drag bars 31 to permit vertical angular 105 adjustment of the supplemental frames 30 in respect to said drag bars.

The two supplemental frames 30 are rigidly connected by a transverse tie-bar 35 having at its intermediate portion a yoke, the vertical members of which are mounted 5 in swiveled bearings 36 on the vertical members of the yoke 28 with freedom for vertical sliding movement therein. The ends of the tie-bar 35 rest upon the supplemental frames 30 and are rigidly but adjustably secured thereto by clips 37. The purpose of thus connecting the supplemental frames 30 in respect to the tie-bar 27 is to cause said frames to move laterally in 10 respect to the main wheels 24 when angular steering movement is imparted thereto.

A gang of ground-working tools in the form of spring teeth 38 is carried by each supplemental frame 30, and each of said teeth is secured to the respective frame 30 15 by a post 39 having on its lower end a horizontal stud 40. The upper ends of the teeth 38 are made segmental to fit around the studs 40 and have formed therein longitudinal slots 41 through which and aligned bores in said studs extend clamping bolts 42 by means of which said teeth may be clamped to the studs 40. Obviously, by circumferentially adjusting the teeth 38 on the studs 40 by means of the bolts 42, the 20 points of said teeth may be set either forward or backward, at will.

The posts 39 are rigidly secured to the supplemental frames 30 with freedom for vertical adjustment by blocks 43, clamping bars 44, and nut-equipped draw-bolts 45. On each vertical face of each block 43 is integrally formed upper and lower pairs of horizontally projecting lugs 46. The lugs 46, on one side of the blocks 43, are arranged to engage the horizontal edges of the side members of the supplemental frames 30 and interlock said blocks thereto against angular movement, and the lugs 46 on the other side of said blocks are arranged to 25 engage the vertical edges of the bars 39 and interlock said posts thereto with freedom for vertical sliding movement. By reference to Fig. 8, it will be noted that the blocks 43 are reversible so that the lugs on either side thereof may be arranged to interlock with the side members of the supplemental frames 30 or to interlock with the posts 39. The clamping bars 44 extend transversely across the outer faces of the 30 posts 39 between the respective upper and lower pairs of lugs 46, and the bolts 45 extend through aligned bores in the side members of the supplemental frames 30, blocks 43 and ends of the clamping bars 44. By 35 reference to Fig. 2, it will be noted that there is formed in the side members of the supplemental frames 30 a plurality of longitudinally spaced bores for the draw-bolts 45, so that the blocks 43 may be adjusted 40 either forward or backward on said frames.

To support the supplemental frames 30 with the teeth 38, set into the ground at a predetermined depth, caster wheels 47 are journaled in brackets 48 having stems swiveled in said frames. Opposing collars 48', 70 on the stems of the caster wheel brackets 48, engage the supplemental frames 30 and support the same in different vertical positions. Referring more specifically to the spring teeth 38, it may be here stated that the points 75 of said teeth, at the junction with the bodies thereof, are somewhat wider than said bodies, and that the outside angle of said points is materially greater than the inside angle thereof, as shown in Fig. 9.

To independently or simultaneously raise and lower the supplemental frames 30, the following connections are provided, to wit:—

Extending parallel to the transverse portion of the axle member 14 and slightly forward thereof is a square rock-shaft 49 having secured to its ends hubs 50, the inner ends of which are journaled in bearing brackets 51 rigidly secured to the side members of the main frame 11. Loosely fulcrumed on the outer end of each hub 50 is a latch lever 52, and co-operating therewith is a lock segment 53, having laterally projecting stop lugs 54 which limit the oscillatory movement of said lever. The lock segments 53 are integrally formed with the hubs 50 between the bearing brackets 51 and latch levers 52 for common oscillatory movement therewith. Inner and outer 100 clamping collars 55 and co-operating washers 56, on the rock-shaft 49, are provided for holding the hubs 50 against axial movement on said rock-shaft.

Each supplemental frame 30 has attached thereto, at substantially its longitudinal center, a lifting chain 58 adjustably connected by a hook 59 to the intermediate portion of the overlying latch lever 52. The rock-shaft 49 is oscillated and held in different oscillated positions by a rearwardly projecting latch lever 60 and co-operating segment 61. Said latch lever 60 is intermediate secured to the rock-shaft 49, between the right-hand inner clamping collar 115 55 and co-operating washer 56, for movement therewith, and its lock segment 61 is rigidly secured to the main frame 11.

Obviously, by manipulating the latch lever 60, the latch levers 52 will also be oscillated therewith for the reason that they are locked to the rock-shaft 49 by the lock segments 53. It is further evident that when the latch levers 52 are oscillated with the rock-shaft 49, the supplemental frames 30 will be simultaneously raised or lowered by the flexible connection 58. These flexible connections 58 also permit the supplemental frames 30 to be slightly independently vertically adjusted. It is, of course, understood 130

that when one of the supplemental frames 30 is raised or lowered, the connected tie-bar 35 will also move, owing to the swiveled connections of its bearings 36, and thereby 5 transversely move the other supplemental frame 30. The member 35 is loosely fitted in member 36 so that a sliding movement between these members is permitted. The flexible connections 58 also permit independent adjustment of the supplemental frames by 10 securing different links of said chains on the hooks 59. By vertically adjusting the posts 39 on the blocks 43, further means is provided to regulate the depth at which the 15 points of the teeth 38 enter the ground may be varied at will.

To assist in raising the lever 60 to lift the supplemental frames 30, the pull on the machine is utilized and the following connections 20 are provided for performing this function, to wit:

Journalized in bearings 62 on the main frame 11, is a transverse rod 63 having on its ends depending crank arms 64, the lower 25 ends of which are connected by links 65 therein having hooks at their outer ends which as shown in Fig. 2, pass through lugs on the lower ends of the bearing sleeves 18. A link 66 also connects the short end 30 of the lever 60 to the outer end of the right-hand crank arm 64. Obviously, by unlatching the lever 60 from the lock segment 61, the pull on the frame 11 will rock the axle portions 14, 16 and 18 forward under the 35 retarding action of the wheels 24. This retarding action of the wheels 24 will hold the short end of the lever 60 through the links 65 and 66 and thereby, under the advance movement of the frame 11 in respect 40 to the wheels 24, cause the lever 60 to swing upward on its fulcrum. The operator, by holding the lever 60, may control this upward movement of said lever.

To lower the supplemental frames 30 and 45 set the teeth 38 into the ground, the operator may pull the lever 60 toward himself, which is an easy operation for the reason that the weight of said frames greatly assists this operation. Preferably, the vertical 50 portions of the axle will be in a slightly rearwardly inclined position when the teeth 38 are in the ground, and, when said teeth are out of the ground, said vertical portions of the axle will be inclined slightly forward 55 so that the horizontal movement of the wheel trunnions 21 is only slight from one side to the other of a true vertical position. This horizontal movement of the wheel trunnions 21 also makes the operation of the 60 lever 60 relatively easy for the reason that the lifting movement of the main frame is only very slight.

Shields 67 are provided to prevent lumps from falling on small plants between the 65 two gangs of teeth 38, but permits fine dirt

to work therethrough and around the plants. These shields 67 are secured to the rear ends of rearwardly projecting arms 68 attached to the drag-bars 31 and are in the form of vertically spaced diverging fingers of steel 70 wire which extend rearward and are located close to the inner edges of the two foremost teeth 38. By making the shields 67 of steel wires, the vibratory movement thereof will prevent clogging.

75

What I claim is:—

1. A cultivator including a main frame, crank-arm-equipped trunnions connected to the main frame by vertical pivots, wheels journalized on the trunnions, a tie-bar connecting said crank arms, two laterally spaced supplemental frames, ground-working tools carried by the supplemental frames, and a tie-bar rigidly connecting the supplemental frames and secured for common transverse movement in respect to the first noted tie-bar but with freedom to permit raising and lowering movements of the supplemental frames in respect to the main frame.

90

2. A cultivator including a main frame, crank-arm-equipped trunnions connected to the main frame by vertical pivots, wheels journalized on the trunnions, a tie-bar connecting said crank arms, and having an intermediate arch, two laterally spaced supplemental frames, ground-working tools carried by the supplemental frames and having an intermediate arch, and guides on the first noted tie-bar in which the arms of the last noted arch are mounted for vertical movement and limited angular movement.

95

3. A cultivator including a main frame, crank-arm-equipped trunnions connected to the main frame by vertical pivots, wheels 105 journalized on the trunnions, a tie-bar connecting said crank arms, two laterally spaced supplemental frames, ground-working tools carried by the supplemental frames, means flexibly connecting the supplemental frames 110 in respect to the main frame, a tie-bar rigidly connecting the supplemental frames, means connecting the tie-bar of the supplemental frames to the first noted tie-bar for common transverse movement, but with freedom for vertical angular and raising and lowering movements in respect thereto, and means for raising and lowering the supplemental frames.

115

4. A cultivator including a main frame, 120 crank-arm-equipped trunnions connected to the main frame by vertical pivots, wheels journalized on the trunnions, a tie-bar connecting said crank arms, two laterally spaced supplemental frames, ground-working tools 125 carried by the supplemental frames, means flexibly connecting the supplemental frames in respect to the main frame, a tie-bar having an intermediate arch rigidly connecting the supplemental frames, bearings connected 130

to the first noted tie-bar by horizontal swivels and having the vertical members of the arch of the tie-bar connecting the supplemental frames slidably mounted therein, and means 5 for raising and lowering the supplemental frames.

5. A cultivator including a main frame, crank-arm-equipped trunnions connected to the main frame by vertical pivots, wheels 10 journaled on the trunnions, a tie-bar having an intermediate arch connecting said crank arms, two laterally spaced supplemental frames, ground-working tools carried by the supplemental frames, means flexibly connecting the supplemental frames in respect to the main frame, a tie-bar having an intermediate arch rigidly connecting the supplemental frames, bearings connected to the first noted tie-bar on each side of its arch 20 and having the vertical members of the arch of the tie-bar connecting the supplemental frames slidably mounted therein, and means for raising and lowering the supplemental frames.

25. 6. A cultivator including a main frame, a crank axle mounted on the main frame, wheels journaled on the crank axle, two laterally spaced supplemental frames flexibly connected in respect to the main frame, 30 a transverse rock-shaft having on its ends hubs journaled in bearings on the main

frame, a lever intermediately secured to the rock-shaft for oscillating the same and having a co-operating lock segment secured to the main frame, hanger arms on the main frame, a link connecting one of said hanger arms to the short end of said lever, a pair of links connecting said hanger arms in respect to the vertical member of the crank axle, a pair of levers pivoted on said hubs 40 and having co-operating lock segments rigidly secured to said hubs, and flexible connections between the supplemental frames and said pair of levers.

7. A cultivator including a main frame, 45 main wheels turnable about a vertical axis, two laterally supplemental frames, means connected to said supplemental frames for moving the same laterally when the wheels are turned on their vertical pivots, a frame 50 rigidly connecting said supplemental frame and a slidale and swivelling connection between said latter frame and said means whereby either of said supplemental frames can be raised.

In testimony whereof I affix my signature in presence of two witnesses.

JOSEPH J. KOVAR.
